UNITED STATES PATENT OFFICE.

HENRY WEIL, OF NEW YORK, N. Y.

ART OF PRODUCING LACE EFFECTS.

1,216,637.

Specification of Letters Patent. Patented Feb. 20, 1917.

Application filed February 19, 1916. Serial No. 79,299.

To all whom it may concern:

Be it known that I, HENRY WEIL, a citizen of the United States, and resident of the city, county, and State of New York, have 5 invented certain new and useful Improvements in the Art of Producing Lace Effects, of which the following is a specification.

This invention relates to the art of producing lace effects, the object being to provide 10 a method by means of which the effect of lace insertion in a piece of material may be obtained without inserting a real lace medallion or lace insertion in a cut out space in the material in the usual manner. 15 The object of the present invention is to enable the manufacturer of art embroideries to produce an article at reduced cost, which will closely resemble and produce substantially 20 the same transparent effect as a real lace insertion.

In the accompanying drawings Figure 1 is a face view of a piece of material in which a lace insert effect has been produced according to this invention.

25 Fig. 2 is a sectional perspective view showing a portion of the material with the design for lace effect embroidered on the back-ground.

In carrying out the invention I provide 30 a dark background, preferably black, in or on the desired material, a portion of which is shown at 1 in the drawings, such background occupying the space or spaces which would ordinarily be cut out to receive the 35 lace medallion or insertion. This background may be of contrasting color from that of the material itself or may be of the same color. This background, which is indicated by the reference character 2 in the 40 drawings, is adapted to carry the design, indicated at 3, representing the lace effect, which may be stamped or printed thereon. This printed design may form a guide for working or embroidering the design upon 45 the material, a small portion of such worked or embroidered design being shown at 4 in Fig. 3, or the stamped or printed design for lace effect may be used upon the back-ground without embroidering.

50 The pattern or design for lace effect is applied, as shown, to the background in a manner identical with the manner in which an actual lace insertion would be applied in an opening corresponding to the back-ground, the edges of the pattern being so

disposed with reference to the edges of the background as to give the effect of the lace being attached at its edges to the material while such arrangement, in conjunction with the contrasting colors of the pattern 60 for lace effect and the background, causes the latter to present the appearance of an opening in the material in which the lace is inserted.

The material when prepared according to 65 this method may be used for various purposes, such as pillow tops, draperies, buffet or bureau scarfs, etc. In fact, it is adapted for use for any purpose for which real lace insertions or edgings may be used, and the 70 effect of the same, particularly when viewed from a little distance, is identical with that produced by real lace insertions or edgings, while it will be obvious that the completed object may be manufactured at much less 75 cost.

What I claim and desire to secure by Letters Patent is:

1. The art or method of producing lace insertion effects which consists in providing 80 upon a piece of material a background representing an opening cut therein and adapted to be embroidered over from margin to margin and in different directions, so as to produce inclosed areas, placing upon said 85 background a design for lace effect, said design and background being of contrasting colors adapted to give the appearance of a lace insertion in an opening in said piece of material, and providing a margin to the 90 background for a substantial distance laterally of a contrasting color from the background proper.

2. An article of manufacture comprising a piece of material having upon a portion 95 thereof a background representing an opening cut therein, a design for lace effects upon said background, said design and background being of contrasting colors adapted to give the appearance of a lace insertion 100 in an opening in said piece of material, the margin to the background for a substantial distance laterally being of a contrasting color from the background proper and the background adapted to be embroidered over from 105 margin to margin and in different directions, so as to produce inclosed areas.

Signed at the city, county and State of New York, this 17 day of February 1916.

HENRY WEIL.
